UNITED STATES PATENT OFFICE.

THOMAS SHIPLEY, OF YORK, PENNSYLVANIA.

ICE-MAKING MACHINERY.

SPECIFICATION forming part of Letters Patent No. 659,610, dated October 9, 1900.

Application filed September 8, 1900, Serial No. 29,365. (No model.)

To all whom it may concern:

Be it known that I, THOMAS SHIPLEY, a citizen of the United States, residing at York, in the county of York and State of Pennsylvania, have invented a certain new and useful Improvement in Ice-Making Machinery, of which the following is a specification.

My invention relates to that class of ice-making machines in which the ammonia is kept in circulation in a pipe-circuit connected with a condenser, to which the ammonia after having done its work is returned by means of one or more compressors. It has more particular reference to the means for preliminarily cooling the water before it is admitted to that portion of the apparatus in which it is frozen, the object being to obtain a compact efficient cooling system which will act regularly and with uniformity upon the water.

To this end my invention consists of the devices and combinations which will first be described in connection with the accompanying drawing and will then be more particularly pointed out in the claim.

The drawing is a diagrammatic representation of an apparatus embodying my invention.

The particular apparatus illustrated in the drawing is an ice-making plant operating on what is known as the "can" system; but the invention is applicable to other systems as well—such as the "plate" system, the "block" system, &c.

A is the condenser for the ammonia or other refrigerant.

B B' are two single-acting compressors driven in the usual way.

C is a freezing-tank of the can type containing the usual freezing appliances.

From the outer end of the condenser there leads a pipe 1 into a reservoir X, at which point it has a controlling-valve x. From the reservoir X the refrigerant is conducted by pipe 2 to the freezing appliances in tank C, through which it passes in the customary way, and thence out through pipe 3 back to the compressors B B', by which it is returned to the condenser through pipes 4 5 6. Pipe 2 is provided with a reducing-valve y, by which the "back pressure" in the freezing part of the system is regulated. The pipe system thus far traced is what may be called the "freezing-pipe" circuit.

D is the tank for holding the preliminarily-cooled water, which is conveyed from that tank to the freezing-tank C by a pipe p. The 55 supply of water is drawn through a pipe n from any usual or suitable source and after passing through the cooling system is stored in tank D.

The cooling of the water is effected not directly by the ammonia or other refrigerant, but indirectly through the instrumentality of brine, which is first cooled by the refrigerant and then in turn cools the water. The refrigerant which acts upon the brine is not the 65 return gas from the freezing-tank, but is supplied independently of the latter from the condenser, being taken from the reservoir X at any desired pressure. In this way I am enabled to cool the water efficiently and uniformly without danger of prematurely freezing it. What may be called the "cooling-pipe" circuit is as follows: from the outlet end of the condenser A through pipe 1 to reservoir X, thence through a pipe 7, provided 70 with a reducing-valve z, to and through the outer space or jacket of a jacketed coil m, thence through a branch pipe 8 to return-pipe 3, whence it goes to the compressors and back to the condenser. The brine-circuit includes 75 a pump E and pipe connections 9 10 11, by means of which the brine is caused to circulate first through the inner pipe of the jacketed brine-cooling coil m, where it is cooled by the action of the refrigerant, and thence 80 by means of the pump E through the outer pipe or jacket of a jacketed coil l', where it in turn cools the water, which from pipe n 85 circulates through the inner pipe of coil l' and thence passes thoroughly cooled into the 90 storage-tank D. Under this arrangement it will be noted that the return-pipe 3 is common to both systems—the cooling system and the freezing system. The pipe 3 is, in fact, the suction-pipe upon which both of the compressors B B' draw, each of the latter working upon or drawing from both systems.

In lieu of two single-acting compressors one double-acting compressor might be used.

Having thus described my invention, what 100 I claim herein as new, and desire to secure by Letters Patent, is—

In machinery for making ice, the combination substantially as hereinbefore set forth

of the following elements: a refrigerant-condenser; compressors; freezing appliances; brine-cooling appliances; two pipe-lines from the condenser, the one to the freezing system 5 the other to the brine-cooling system and means for regulating the pressure in each line; a return pipe-line common to both systems and to the compressors; and a brine-circuit including means for causing the circulation of brine therein, and water-cooling ap-

pliances through which the water circulates and is preliminarily cooled by the brine, before entering the freezing appliances.

In testimony whereof I have hereunto set my hand this 4th day of September, 1900. 15

THOMAS SHIPLEY.
